United States Patent Office

Des. 227,194
Patented June 5, 1973

227,194

TAG HOLDER

Donald M. Palmer, 2627 E. 68th Ave.,
Portland, Oreg. 97206

Filed May 17, 1971, Ser. No. 144,395

Term of patent 14 years

Int. Cl. D8—08

U.S. Cl. D8—243

The figure is a perspective view of a tag holding device embodying my new design.

I claim:

The ornamental design for a tag holder, as shown.
